UNITED STATES PATENT OFFICE.

WILLIAM C. BRIGGS, OF WINSTON SALEM, NORTH CAROLINA.

CUTTER FOR CIGARS.

No. 838,298.

Specification of Letters Patent.

Patented Dec. 11, 1906.

Application filed February 19, 1906. Serial No. 301,903.

To all whom it may concern:

Be it known that I, WILLIAM C. BRIGGS, a citizen of the United States, residing at Winston Salem, county of Forsyth, and State of North Carolina, have invented certain new and useful Improvements in Cutters for Cigars, of which the following is a specification.

My invention relates to cutters used for severing the tips or mouth ends from cigars; and the object of my invention is to improve the construction of such cutters and provide them with means for severing cigar-bands.

The bands now so extensively used on cigars are usually removed therefrom just before smoking by being slipped off endwise of the cigar, cut with a knife, or torn. Sometimes the bands so tightly inclose the cigars that they cannot readily be slipped or torn off without injury to the cigars, and when a pocket-knife is used to cut the bands care must be taken to avoid cutting or puncturing the tobacco.

According to my invention I combine with a cutter for severing the cigar-tips a cutter for the bands, and preferably so construct the cutter members that a shear cut may be given by the band-cutter in the act of opening the tip-cutters, while a shear cut is given by the tip-cutters in the act of closing them.

In the accompanying drawings, Figure 1 is a perspective view of my combined tip and band cutter, showing also how it is grasped and operated when cutting a cigar-band. Fig. 2 is a side elevation of the cutter, partly in section, in the act of cutting a band. Fig. 3 shows a local section through the pivotal connection of the cutter members. Fig. 4 shows a transverse section on the line $x-x$ of Fig. 2. Fig. 5 shows a transverse section through the tip and band cutters.

In the embodiment of my invention shown in the drawings the tip-cutter is shown as comprising two members A and B, hinged together at one end and provided at their opposite ends with suitable handles or finger-rings. The member A is formed between its opposite ends with a semicircular recess having a sharp beveled edge a , and the member B has a similar recess and like beveled edge b . When the cutter is opened or the members spread apart, the tipped end of a cigar

is placed between the cutting edges, and then by bringing the edges together the tip is severed. 55

D indicates a cutter for cigar-bands. It is preferably formed, as shown, in the shape of a finger having a tapered, but not sharp, outer end, a smooth under surface, and a comparatively flat inner or upper surface formed 60 with a cutting edge d , coöoperating with a cutting edge x on the member A, so as to produce a shear cut on the band X. The band-cutter D may be connected to move with the member B of the tip-cutter in the manner 65 shown in Fig. 3. As there illustrated, the pivot-pin c , which connects the members A and B has a square head arranged in a square recess in the member B, and a squared outer end projecting beyond the member A, which 70 extends into a square socket into the hub of the band-cutter D. A screw E, having a large head, engages the pivot C and holds the parts in place, permitting the member A to turn freely on the pivot, but causing the 75 band-cutter to always move with the tip-cutter member B. By this arrangement when the tip-cutter is closed, as shown in Fig. 1, the cutter D may be slipped under a band in the manner indicated without injury to 80 the cigar and then by spreading the tip members apart, as shown in Fig. 2, the edges d and x may be brought together and the band neatly severed.

So far as I am aware I am the first to combine a cigar-band cutter with a cigar-tip cutter, and while I have illustrated and described the best way now known to me of carrying out my invention I do not wish to be limited to the details of construction 90 specified.

I claim—

1. A cigar-tip cutter provided with a thin flat band-cutting finger coöoperating with a cutting edge on the tip-cutter and adapted to 95 pass between a cigar-band and a cigar, substantially as described.

2. A cutter for cigars, comprising tip-cutter members movable relatively to each other and a band-cutter movable with one of the 100 tip-cutter members.

3. A cutter for cigars, comprising two cutter members pivotally connected with each other having opposing tip-severing edges and

one of which has a band-severing edge and a band-cutting finger having a cutting edge co-operating with said band-severing edge.

4. A cutter for cigars, comprising tip-cutting members pivotally connected with each other and a band-cutting finger extending along the outer edge of one of the members.

In testimony whereof I have hereunto subscribed my name.

WILLIAM C. BRIGGS.
